UNITED STATES PATENT OFFICE

2,654,231

REFRIGERATING COIL MOUNTING IN
CABINETRobert L. Eichhorn, Evansville, Ind., assignor to
International Harvester Company, a corpora-
tion of New Jersey

Application July 15, 1950, Serial No. 174,030

7 Claims. (Cl. 62—116)

1

This invention relates to refrigerating apparatus and more particularly to means for securing a condenser coil to the outer shell of a refrigerating cabinet.

In refrigerating cabinets formed with an inner liner spaced within an outer shell, it is becoming increasingly common to wrap the evaporator coils around the outside of the inner liner and to place the condenser coil against the inner wall surfaces of the outer shell. The refrigerant evaporates in the evaporator coil which cools the walls of the inner liner so as to maintain the food storage compartment at a predetermined temperature. The hot refrigerant gases are condensed in the condenser coil and the heat from these gases will be conducted to the walls of the outer shell and then dissipated to air surrounding the cabinet. This will cause the temperature of the walls of the outer shell to be slightly warmer than the air so that there will be no moisture condensed on the exterior of the cabinet.

Since it is necessary to have both the evaporator coil and the condenser coil in good thermal contact with the inner liner and outer shell respectively, some means must be provided for holding the coils against the liner and shell. The method most commonly used is to position coil clamps over the coil and then spot weld them to the adjacent wall. However, it is undesirable to weld clamps on the exposed walls of the outer shell since the points of contact of the pressure welds would cause indentations on the outer surface of the walls and thus mar the smooth surface of the wall.

An object of the present invention is to provide a refrigerator cabinet with an evaporator coil positioned adjacent the outer surface of the inner liner and a condenser coil positioned adjacent the inner wall surfaces of the outer shell.

Another object is to provide novel means for attaching a coil to the outer shell of a refrigerator cabinet whereby no spot welding will be required on the walls which are exposed to view.

Still another object is to provide a refrigerator cabinet in which a retainer member cooperates with a clamp member for securing a condenser coil against an inner wall surface of the outer shell of the refrigerator cabinet.

A further object is to provide a refrigerator cabinet in which a clamp member secures a portion of a coil to a wall member, said clamp member being deflected so that it will force the coil tightly against the wall member.

Still further objects and advantages of the in-

2

vention will be apparent from the following description of the illustrative embodiment shown in the accompanying drawings, in which:

Fig. 1 is a perspective view of a refrigerator cabinet.

Fig. 2 is a sectional view taken along the line 2—2 of Fig. 1.

Fig. 3 is a perspective view of a portion of the outer shell of the refrigerator cabinet.

Fig. 4 is a perspective view of another portion of the outer shell of the refrigerator cabinet.

Fig. 5 is an enlarged elevational view of the longitudinal clamp member of Figs. 3 and 4.

Referring to the drawings, there is shown a refrigerator cabinet 10 such as a home freezer or freezer chest. This cabinet broadly includes a base 11, an outer shell 12 secured to the base, an inner liner 13 spaced within the outer shell, insulating material 14 disposed between the outer shell 12 and the inner liner 13, a door 15 hingedly mounted to the outer shell, and a condensing unit housing 16 which is detachably mounted on base 11. An evaporator coil 17 is secured to the outer wall surfaces of inner liner 13, and a condenser coil 18 is secured to the inner wall surfaces of the outer shell 12. A motor-compressor unit is located under housing 16 but is not shown since it is not a part of the present invention. A grill 19 is provided in the front wall of housing 16 through which cooling air will be drawn and circulated over the motor-compressor unit.

The condenser coil 18 has one end connected to the outlet side of the compressor and the other end connected to the evaporator coil. The other end of the evaporator coil is connected to the inlet side of the compressor. Very briefly, the refrigeration system operates as follows: refrigerant gases are compressed by the compressor and discharged under pressure to the condenser coil 18 where heat is dissipated from the gases by the walls of the outer shell 12 causing the gases to be condensed into a liquid; the liquid refrigerant then flows through evaporator coil 17 where it absorbs heat from the walls of the inner liner 13 and is converted into gases which then flow back to the compressor to repeat the cycle.

Outer shell 12 is constructed from sheet metal 50 to have front wall 20, left end wall 21, back wall 22 and right end wall 23. The bottom edges of the walls are bent inwardly toward each other to form a flange 24 to which a sheet metal bottom 25 is secured. The upper edges of the walls are 55 bent downwardly and outwardly toward each

other to form a flange 26 to which a sheet metal top 27 is secured. The outer shell 12 is secured to the base 11 by a plurality of nuts and bolts 28.

other to form a flange 26 around the periphery of the door opening.

The inner liner 13 is formed from sheet metal to have four vertical walls parallel to the outer shell walls and a bottom parallel to bottom 25. The walls of the inner liner 13 define a food storage compartment 27. The evaporator coil 17 is wrapped around the liner and is secured against the walls and bottom by a number of coil clamps 28 which are spot welded to the walls and bottom. The upper edge portions of the inner liner walls are bent downwardly and outwardly to form a flange 23 around the periphery of the door opening. A breaker strip member 30 bridges across the top edges of inner liner 13 and outer liner 12 and is secured to flanges 26 and 28 in any suitable manner.

The condenser coil 18 comprises a tube bent into top turn 31, intermediate turn 32 and bottom turn 33. The top turn 31 is positioned adjacent flange 26 and is secured against the walls of the outer shell 12 by metal clips 34 which are spot welded to flange 26 at spaced intervals. Bottom turn 33 is positioned adjacent flange 24 and is secured against the walls of the outer shell 12 by bent-in tabs 35 which are formed along the edge of bottom 25.

The intermediate turn 32 is secured to the back wall 22 and right end wall 23 by metal coil clamps 36 which are spot welded to the walls. However, this type of coil clamp is not desirable on front wall 20 and left end wall 21 since both of these walls are exposed to view and spot welding would mar the wall surface.

The intermediate turn 32 is secured to end wall 21 by a coil retainer 37 and a clamp member 41 as shown in Fig. 3. The coil retainer is formed as a U-shaped channel of the proper dimension to fit over the tube 32 with legs 39 and 40 slightly shorter than the outer diameter of the tube. One end of the coil retainer is curved to fit around the corner between left end wall 21 and back wall 22 and is supported by bracket 38 which is spot welded to the back wall 22.

A clamp member 41 is provided for holding the coil retainer in place. As shown in Fig. 5 this clamp member is formed from metal into a bowed member having ends 42 and 43 bent at substantially right angles thereto and bent in edge portions or flanges 44 and 45 for added strength. In assembling the clamp member 41 it is first positioned substantially perpendicular to coil retainer 37 with end 43 positioned under bracket 46 which is secured to bottom 25 by spot welding. End 42 is then forced inwardly toward wall 21 and spot welded to flange 26. In this assembled position the clamp member 41 is deflected from its bowed free shape to be substantially parallel to the end wall 21 so that it bears against retainer 37 with sufficient force to hold the intermediate turn 32 tightly against the left end wall for its entire length.

As shown in Fig. 4 the intermediate turn 32 is secured against the front wall 20 in a similar manner. A U-shaped coil retainer channel 47 having legs 49 and 50 slightly shorter than the outer diameter of the tube is positioned over the turn 32 with one end supported by bracket 48 which is secured to end wall 23. The retainer 47 is positioned over the tube 32 and clamped in place by two clamp members 41 in the same manner as coil retainer as explained above, so that the intermediate turn 32 is secured tightly against the front wall for its entire length.

Having illustrated and described a preferred embodiment of the present invention, it should be apparent to those skilled in the art that various modifications may be made without departing from the spirit of the invention or from the scope of the appended claims.

What is claimed is:

1. In a refrigerator cabinet, an inner liner spaced within an outer shell, a condenser coil disposed adjacent the inner walls of said outer shell, means for attaching said coil to an exposed wall of said outer shell, said means comprising a bracket and a retainer member and a clamp member, said bracket secured to an unexposed wall of said outer shell, said retainer member having a groove which fits over a portion of said coil, an end of said retainer member supported by said bracket, said clamp member having a central portion and two end portions, said central portion positioned against said retainer member with said end portions deflected toward said wall and secured to adjacent portions of said cabinet, said coil being secured between the retainer member and the exposed wall.

2. In a refrigerator cabinet, an outer shell having a coil disposed adjacent the inner wall surfaces thereof, a retainer member having spaced apart legs connected by a web portion, said retainer being positioned with said legs fitting over a portion of said coil, said legs being slightly shorter than the outer diameter of said coil, and means for clamping said coil against said wall, said means comprising a clamp member having a central portion and end portions, said clamp member being disposed with said central portion abutting said web portion and said end portions deflected toward said wall and secured to portions of said cabinet adjacent to said wall.

3. In a refrigerator cabinet, an outer shell having a coil disposed adjacent the inner wall surfaces thereof, a retainer member having spaced apart legs connected by a web portion, said retainer member being positioned with said legs fitting over a portion of said coil, said legs being shorter than the outer diameter of said coil, and means for clamping said coil against said wall, said means comprising a longitudinal clamp member having end portions and a central portion which is provided with bent out edge portions, said clamp member being positioned transversely to said retainer member with said central portion abutting said web portion and said edge portions extending away from said web portion, said end portions being deflected toward said wall and secured to portions of said cabinet adjacent to said wall.

4. In a refrigerator cabinet, an outer shell having walls provided with top and bottom flanges, a coil disposed adjacent the inner surfaces of said walls, and means for securing said coil to an exposed wall of said outer shell, said means comprising a bracket and a retainer and a clamp, said bracket being secured to an unexposed wall of said outer shell, said retainer being provided with spaced apart legs connected by a web portion and being positioned with said legs fitting over a portion of said coil with one end thereof supported by said bracket, said clamp being disposed with a central portion thereof abutting said web portion and end portions thereof being deflected toward said wall and secured to said flanges.

5. In a refrigerator cabinet, an outer shell

having walls provided with top and bottom flanges, a coil disposed adjacent the inner surfaces of said walls, and means for securing said coil to an exposed wall of said outer shell, said means comprising a bracket and a retainer and a clamp, said bracket being secured to an unexposed wall of said outer shell, said retainer being provided with spaced apart legs connected by a web portion and being positioned with said legs fitting over a portion of said coil with one end thereof supported by said bracket, said clamp having end portions and a longitudinal central portion which is provided with bent out edge portions, said clamp being positioned transversely to said retainer with said central portion abutting said web portion and said end portions being deflected toward said wall and secured to said flanges.

6. In a refrigerator cabinet having a condenser coil disposed adjacent the inner surface of an outer wall of said cabinet, means for mounting a straight section of said condenser coil in thermal contact with said inner surface of said outer wall, said means comprising a pair of flanges disposed in a spaced apart relation along the inner surface of said outer wall parallel to said section and substantially at the edges of said wall, said flanges formed by folded portions of said outer wall, a rigid retaining member comprising a longitudinal member having a pair of

5
10

longitudinal ribs depending therefrom to form a groove, said ribs having a lesser depth than the diameter of said condenser coil, said retaining member positioned adjacent said straight section of said condenser coil with said section within said groove, resilient clamping members of a length substantially equal to the distance between said flanges, said resilient clamping members disposed transversely against said longitudinal member of said retaining member, and means for securing the ends of said clamping members to said flanges to mount said section in thermal contact with the inner surface of said outer wall.

15
20
25

7. In a cabinet as claimed in claim 6, each of said resilient clamping members comprising a longitudinal member having a pair of longitudinal ribs depending therefrom, and each of said clamping members formed to deformably bow convexly toward the side from which said longitudinal ribs depend.

ROBERT L. EICHHORN.
